JOHN A. DEMUTH, OF OBERLIN, OHIO.

WORKMAN'S TIME-RECORDING SYSTEM.

1,267,989.

Specification of Letters Patent. Patented May 28, 1918.

Application filed April 6, 1917. Serial No. 160,302.

To all whom it may concern:

Be it known that I, JOHN A. DEMUTH, a citizen of the United States, residing at Oberlin, in the county of Lorain and State 5 of Ohio, have invented a certain new and useful Improvement in Workmen's Time-Recording Systems, of which the following is a full, clear, and exact description, reference being had to the accompanying drawings.

This invention relates to a system for recording the time of arrival and departure of workmen. The primary objects are to provide such a system which may be simple, 15 effective and very difficult to defraud. Another object is to provide a system which may be easily put into practice and be capable of use with comparatively inexpensive equipment. Still another object is to so arrange the system that it may render the work 20 of the time clerks comparatively easy and facilitate accurate and rapid computation of the time for which each workman is to be paid.

It has heretofore been common practice to provide time clocks equipped with a mechanism for recording the time of entry and departure on an individual card for each workman. Such a system requires a comparatively 30 expensive equipment including such a clock and printing mechanism, and racks for the cards of each group of workmen. Another method is the use of a clock equipped with printing mechanism adapted to record 35 the time of actuation for a number of employees on a record sheet by the individual workman moving a lever to his number on a dial and actuating the lever at that point. Such systems lend themselves readily to 40 fraudulent record by the workmen, it being a comparatively easy matter, for example, for one workman to "ring in" or "punch the card" for another.

To avoid the above and other methods 45 of fraud in the recording of the amount of time each employee works, I have devised a system wherein the workman records the time by copying a symbol or code sign displayed by a clock and actuated so that each 50 symbol corresponds to a certain time. Thus it is only necessary to provide one of such clocks in an entry room, in view of many workmen who simultaneously may record their times of entry or departure on various record strips provided for that pur-

pose. These record strips may conveniently be contained in suitable casings positioned for convenient registration by several groups of workmen, a suitable number of workmen being assigned to register at each place.

The record strip carrying the names and numbers of various workmen preceded by the sign or symbol corresponding to the time of entry or departure may be removed from the casing by the time clerk, and the record 60 tabulated on a summarizing sheet on which the time for a pay period may be computed for the group of workmen registering at the place where that record strip was used.

The record strip carrying the names and numbers of various workmen preceded by the sign or symbol corresponding to the time of entry or departure may be removed from the casing by the time clerk, and the record 65 tabulated on a summarizing sheet on which the time for a pay period may be computed for the group of workmen registering at the place where that record strip was used.

To prevent a symbol being repeated to represent the same time for consecutive hour or twelve hour periods, I arrange these symbols so that the number thereof is not the same as the number of periods into which the hour or twelve hours is divided, and cause 70 the symbols to be advanced or changed regularly at the expiration of these periods. Thus the relation of each symbol to the position of the clock hands is constantly changed. This prevents a workman from memorizing 75 a symbol displayed at a certain time and successfully using that symbol to falsely indicate entry at a corresponding later time. For example, the symbol KN, representing 80 8:00 o'clock Thursday, March 1st, may not 85 again represent or correspond to 8:00 o'clock for many days or months.

To illustrate the use of my system, I have shown in the drawings a convenient apparatus for carrying it out, and will now more 90 fully describe the same in connection therewith. The essential characteristics of the invention are summarized in the claims.

In the drawings, Figure 1 is a front elevation of a clock presenting a time symbol; 95 Fig. 2 is a vertical section through the same; Fig. 3 is a transverse vertical section on an enlarged scale illustrating the mechanism controlling the movement of the symbol belt; Fig. 4 is a section at right angles to 100 Fig. 3 substantially on the line 4-4 of that figure; Fig. 5 is a similar section taken substantially on the line 5-5 of Fig. 3; Fig. 6 is a front elevation of a portion of the clock mechanism and the means for controlling 105 the actuation of the symbol belt; Fig. 7 is a perspective view of a casing or container for the record strip, showing the writing openings; Fig. 8 is a view of a portion of a record strip after receiving the signatures and 110

time symbols of the several workmen assigned to the box from which the strip was taken; Fig. 9 shows a portion of a key device for interpreting the symbols.

5 Describing my mechanism by the use of reference characters, 10 indicates a clock casing carrying at its upper portion suitable mechanism actuating the hands of a clock dial 12 and controlling the movement of the 10 symbol belt 14 to present various symbols at an opening 15 in the front wall 13 of the clock casing.

As shown, the clock mechanism proper has a suitable frame 16, carrying a spring 15 17 actuating a gear 18, transmitting movement through intermediate gearing indicated at 19 to a spindle 20 carrying a series of stepped-toothed star wheels 22, each having its teeth offset with relation to the next 20 adjacent wheel to present a series of evenly spaced teeth dividing the hour into a number of equal periods, for example, thirty two-minute periods. Thus, the star wheels are provided with six teeth and arranged to 25 coat with a small lever 23 pivoted at 24 to the frame 16. These levers are connected by flexible members 25 with vertically movable actuating weights 26. As shown, these flexible members 25 are guided over pulleys 30 27 so that they may rise vertically from the weights 26 and then extend inwardly slightly to the operating levers 23, although it is to be understood that the connection between the operating weights and these levers might be a rigid connection or the 35 weights themselves might extend directly to the levers, as mechanical expediency requires. The weights 26 are shown as slidably guided in a block 30 secured to the side 40 wall of the casing 10.

The movement of the spindle 20 and star wheels 22 is in the direction of the arrow indicated in Fig. 6 and as the wheels are rotated the various levers 23 are lifted and then they are released one by one, each dropping from one tooth of its star wheel to the next. In dropping, the corresponding weight 26 is caused to strike the laterally extended end 32 of a lever 31 pivoted 45 at 33 to a bracket 29 extending from the rear wall of the clock casing. The force of the blow raises the right hand end of the lever and withdraws a dog 34, carried by the lever, from engagement with one of the teeth 35 formed in the periphery of one of the flanges 36 of a drum 37 over which the symbol belt 14 is guided. This drum is shown as mounted on a spindle 38 carried by brackets 39 extending from the rear wall, 50 of the casing, and this spindle is shown as driven by constant tension spring actuated mechanism.

The mechanism driving the spindle 38 is mounted in a frame 40 and preferably comprises a spring 44 actuating a gear 42 which

drives a pinion 43 rigid with the gear 44, in turn driving a gear 45 rigid on the spindle 38. A shaft 46 is shown as extending transversely through the clock casing and is provided with a square portion 47 at its outer end to which may be fitted a crank 48 for winding the spring 41. This shaft extends into and is attached to the inner end of the spring and is retained in any position given it by a pawl 49 coacting with a ratchet tooth 50. The outer end of the spring is connected by a clip 51 with the gear wheel 42.

Consequent upon one of the levers 23 dropping off from a tooth of its star wheel, 55 the weight supported thereby will drop from its uppermost position to the transverse head 32 on the lever 31, momentarily overcoming the tension of a spring 53, shown as attached to the lever and to the block 30, thus withdrawing the tooth 34 from engagement with one of the teeth of the flange 36. The spring 41, acting through the gearing described, promptly advances the drum 37 and the belt, while the spring 53 urges 60 the dog 34 into engagement with the flange by overcoming the weight of the member 26, thus causing this dog to engage the next tooth and stop the movement of the drum. The teeth of the flange 36 are preferably so 65 spaced that each advance of the belt presents the next successive symbol to the opening 15. To cause the belt to be advanced accurately, I have provided eyelets 54 therein spaced between the symbols and adapted to 70 be engaged by short rounded pegs or teeth 55 on the drum 37.

The belt 14 may be guided over a corresponding drum in the lower portion of the 75 clock casing, but to provide a longer belt carrying a larger number of symbols without unduly increasing the size of the clock casing, I prefer to provide two rollers 60 spaced apart in the lower portion of the casing and loop the intermediate portion of the belt upwardly over a roller 62 closely adjacent the drum 37 as indicated in Fig. 2. The rollers 60 and 62 are merely guiding 80 rollers or idlers, and they may be arranged in any suitable fashion or additional rollers 110 may be provided to further loop the belt, allowing it to be made still longer or the casing to be more condensed. It will be seen that the forward reach of this belt is arranged close to the front wall 13 of the 85 casing so that the numbers at either side of the opening 15 may not be seen. The belt is preferably protected by a glass closure 63 mounted across the opening 15.

In Fig. 7 I have shown a writing box in 90 which a record strip may be carried. A convenient arrangement for such a box 65 is substantially rectangular, there being a supply roll 66 pivoted at one end and a winding or advancing roll 67 at the oppo- 95

site end, shown as actuated by a ratchet wheel 68 with which a pawl 69 coacts, this pawl being actuated by a lever 70 pivoted in the wall of the box and standing outside thereof. The record strip is guided closely beneath a plate 73 which is provided with a pair of offset writing openings 74 and 75. The workman may write the symbol appearing on the clock, and his name in the opening 74 and then actuate the lever 72 to move the ratchet wheel 68 and take-up roller 67, thus advancing the record strip 64 presenting a blank space at the opening 75, in which he may write his number. 10 This completes his registration, but leaves the number standing while the name and symbol are concealed. The next workman, after writing the symbol and signing his name, notices a number in the opening 20 which reminds him to actuate the lever to advance the record strip and write his own number. The advancing is merely to bring the name in alinement with the number, thus producing a record such as shown in 25 Fig. 8.

A more complete description of the operation of my invention thus far described is as follows: Take for example a factory employing two hundred workmen, an entrance room is provided through which all the workmen must pass in entering or leaving the factory. In this room is mounted the time clock in a conspicuous place, and in various positions from which the symbol 30 at the opening 15 of the clock may be easily read, are placed record strips in the boxes or casings, such as described. A group of workmen are assigned to each box, those of one group preferably having the same 35 rate of pay, although the reason for assignment to a box at a given place or a given number need not be disclosed. Each workman, upon entering the factory, proceeds to the box to which he is assigned, takes a 40 pencil provided for the purpose and noting the symbol displayed by the clock, writes this symbol, for example KN, and then advances the strip by actuating the lever to 45 present a blank space in the opening 75, whereupon he writes his number in that 50 opening. He then passes into the factory, and another workman assigned to that box may register. At the same time several other workmen may be registering at the 55 various boxes. If, for example, twenty workmen are assigned to a box at one point of registration, ten of these boxes are provided for the two hundred workmen. Upon leaving the factory each employee repeats 60 the above operation.

A record thus provided corresponds to that shown in Fig. 8. The time clerk placing the record strip in position each morning or each registration period may stamp 65 or otherwise note the date and time, as in-

dicated in the upper portion of the strip in Fig. 8, and as each man signs the strip is advanced, as described, automatically arranging the names in a consecutive column. The symbols used are preferably letter combinations, the use of combinations of two letters providing a sufficient number. The time clerk transfers the record on this strip to a summarizing time sheet, having thereon the names of the workmen of a particular place of registration, spaces for indicating the time of entering or leaving, and at the same time he checks the correctness of the workmen's entries. 70

In transferring the record from the workmen's record strip to the summarizing sheet, the time clerk, knowing the symbol presented at the time to start work, sees at a glance that all the names appearing above or previous to that symbol and including 75 those using that symbol are on time. To make sure of the correctness of these entries he need only refer to a list of symbols corresponding to their arrangement on the symbol belt to learn whether they are in 80 proper and consecutive order. By the same method he may determine how late those workmen were whose names appear after the symbol. For example, referring to the record strip shown in Fig. 8, he 85 notes that the symbol corresponding to the time for starting work was KN, which corresponds to 8:00 o'clock (Fig. 1). Three names were entered with this symbol, indicating that they all registered within the 90 two minute period of 8:00 o'clock and those preceding these three names, using the symbols TH, KZ, EB, etc., were on time, and he finds that these are correct and in the proper order. Those appearing after the 95 symbol KN, he notes were late, and to determine the time that they are late, he counts the number of symbols between the KN symbol and the symbol written, thereby 100 learning the number of time periods intervening. Such a list of the symbols may be amplified to provide a complete key to 105 the code. 110

A convenient key for use under the varying conditions that arise is illustrated in 115 Fig. 9. This device represents any convenient means for indicating a symbol displayed at a given time. As shown, it comprises a disk 80 pivoted at 81 to a board or plate 82, shown as carried in a suitable 120 frame 84, the zone surrounding the disk being covered by a sheet 85 having its central portion cut out to clear the disk. The disk is shown as carrying at its periphery a row of spaces in which are marked all of the 125 symbols, of the belt 14, in their proper order. At the border at the opening of the sheet 85 are equally arranged spaces containing numerals from 2 to 120, by twos (using all the even numbers inclusive), cor- 130

responding to two hours' time. The symbol bearing belt and the disk 80 have sixty-one symbols, or, in other words, one more than the number of periods in the time required for the belt to make a complete revolution. Thus the belt is out of commensurate relation to clock hands so that it may be constantly changing its relation thereto and will repeat a symbol for a given time only 10 after a great many intermediate revolutions.

In using this key device to determine the symbol displayed either before or after a certain time, it is only necessary to note the 15 symbol and the time of the clock at the present and then rotate the disk to bring the symbol displayed opposite the blank space 87 on the border of the sheet 85, and then count forwardly or backwardly the 20 number of intervals or minutes intervening between the present and the time of the symbol it is desired to learn. For example, assuming that the time clerk, in the course of his work, reaches the record strip, indicated in Fig. 8, on the same morning it was 25 made, he may have either noted the symbol displayed at the time for beginning work, or he may look at the clock, and noting its symbol and the time intervening between 30 that and 8:00 o'clock, move the disk to set the present symbol at the number on the sheet 85 corresponding to the number of minutes elapsed since 8:00 o'clock. In the latter case, say he is ready to work on the strip at 9:36, 35 he notes that ZL is the symbol displayed by the clock at that time and moves the disk 80 to present ZL to 96, the number of minutes since 8:00 o'clock. He then merely has to note the symbol standing opposite the blank space 40 87, which will correspond to the one displayed by the clock at 8:00 o'clock. It will be seen that if it is desired to learn a symbol displayed at a time many hours previous, it is only necessary to move the disk 45 backwardly as many symbols as there are two hour periods intervening, and then treat the number of minutes over the two hour period as just described.

For convenience in counting time both 50 ways, I provide a second zone outside the first on the sheet 85 and carrying the even numbers from 2 to 120 numbered in the opposite order with relation to the inner row of numbers on this sheet. This device 55 may be rendered more convenient by the use of a similar zone of numbers inside the zone of symbols on the disk 80, and a third zone of spaced apart multiples of ten, in red ink, such as 30, 40, 50, etc., serving as indexes to this row of numbers may be convenient.

Any suitable means for rotating the disk 80 may be used. I have found it convenient, however, to provide a series of openings 88 65 through the disk and a groove 89 in the

board on which the disk is mounted. This groove allows a pencil point to be inserted into the openings 88 to rotate the disk.

For the names appearing after the 8:00 o'clock, their symbols may be checked from 70 the code key to learn the time which they are late, but, for convenience, the workmen may be required to write, previous to their names, the number of minutes or the time which they are late. Thus, on the strip 75 (Fig. 8) Edmunson writes the symbol BH, which is displayed between 4 and 6 minutes, and as the clock appears to be approximately five minutes after eight he writes 5 after the symbol and previous to his name: 80 Smith, who follows Edmunson, finds TB presented at six minutes after eight; and Jones, arriving approximately an hour and thirty-five minutes late, enters the displayed symbol ZL. 85

By noting the arrangement of numerals set on the disk in the position illustrated in Fig. 9, it will be seen how readily the respective times of entrance of Edmunson, Smith and Jones may be checked up, the numbers merely guiding the eye more quickly to the symbol to be checked. Thus—5 might be 4 or 6. We note that it is the symbol for 4, and is approximately correct, and therefore is checked and transferred to the time 95 sheet; 6 is TB, very quickly found; one hour and thirty-five minutes late equals ninety-five minutes. Accordingly we look at 94 and 96. We find that symbol ZL indicates ninety-six minutes late. It, being 100 approximately correct, is also checked and transferred to the time sheet.

I have found that registration of each workman takes substantially as long as with present methods, in some cases a few seconds longer, but, owing to the convenience and cheapness of installing this system and arranging for a large number of workmen to register at the same instant, my system has the advantage in these characteristics. 105 Furthermore, it renders simple the task of computing and summarizing the workmen's time. I have found that with a time sheet having the names listed in a vertical column and ruled to show spaces opposite 110 each name for the time of entering and leaving each day throughout a period of pay, the time may be very quickly checked and transferred to such a sheet, eliminating considerable work now encountered in the 115 handling of time cards, or the computations from printed sheets. In such systems the identification of the workman is by number only, and the late and early registrations must be selected from the printed sheets and 120 transferred to still another sheet for computation, which usually involves subtracting "time from time." Accordingly, my 125 system saves time and expense, both in the registration and in the time clerk's office, 130

and secures practically a fraud-proof method of recording the time.

As to the fraud prevention, in the first place the workmen have no temptation to register one for another as in previous systems. Secondly, if they do attempt such fraudulent registration there are many ways of detecting it. In the first place the workmen need not know why they register at a certain box, and if the workman's name appears in the wrong box, owing to such an attempt, the irregularity is immediately discovered and the signature may be examined. If one workman, while making his own registration, stands at the same box and registers for a companion, the similarity of the writing immediately catches the eye of the time clerk, whereupon he investigates the time of arrival of both workmen whose entries appear to be in question. If a workman attempts to remember the symbol presented one morning and uses the same the next, it will be out of order and immediately attract attention of the clerk, or if one workman inside the factory should transmit information to another outside, (as for example by calling out of the window to a fellow workman) such symbol would appear on the record strip after other earlier symbols and could immediately be detected. The above are examples of the ways in which fraud might be attempted, and illustrate a few of the methods of detecting the same.

Having thus described my invention, what I claim is:

1. In a workmen's time recording system, the combination of a clock, a series of cryptic symbols, means controlled by the clock for successively displaying the symbols at predetermined intervals, recording means whereby the workmen may register the time of entry or departure by noting the symbol displayed, and a code to interpret the notations of the workmen.

2. In a workmen's time recording system, the combination of a clock, a series of cryptic symbols, means controlled by the clock for successively displaying the symbols at predetermined intervals, means whereby workmen may note a symbol displayed and a code to determine the time of displaying any certain symbol.

3. In a workmen's time recording system, the combination of a clock, a series of cryptic symbols, and means for advancing and displaying the symbols, said means being controlled by the clock, and a record sheet on which workmen may register time of entry or departure by entering the symbol displayed.

4. In a workmen's time recording system, the combination of means carrying a plurality of cryptic symbols and adapted to display only one symbol at a time, mecha-

nism for advancing the symbols at measured time intervals, whereby the workmen may register the time of entry by copying the symbol displayed opposite an entry identifying themselves.

70

5. In a workmen's time recording system, the combination of means carrying a series of cryptic symbols, a casing containing such means and having an opening through which one of said symbols may be visible, means for advancing the symbols to present them in succession at predetermined intervals, a record strip, means containing said record strip and having a writing opening where workmen may make an entry identifying themselves, and record the symbol displayed.

75

6. In a workmen's time recording system, the combination of means carrying a series of cryptic symbols, a casing containing such means and having an opening through which one of said symbols may be visible, means for advancing the symbols to present them in succession to said opening at measured intervals, a record strip, a casing inclosing said record strip and having a writing opening at which workmen may make an entry identifying themselves and record the symbol displayed, and means for advancing the strip to conceal the last written symbol.

80

7. In a workmen's time recording system, the combination of a clock, means carrying a plurality of cryptic symbols, a casing surrounding said means and adapted to display one symbol at a time, means connecting the symbol carrying means with the clock mechanism to cause the symbols to be advanced at measured intervals, and means whereby a workman may record a definite time by copying the symbol displayed.

85

8. In a workmen's time recording system, the combination of a belt having thereon a series of cryptic symbols, a casing containing the belt and having an opening displaying one symbol at a time, mechanism for advancing the belt periodically to display the successive symbols, a record sheet on which workmen may note symbols to indicate corresponding times.

90

9. In a system of the character described, the combination of a belt having thereon a series of successively arranged code symbols, rollers carrying the belt, a casing in which the rollers are mounted and inclosing the belt and having an opening adapted to display only a portion of the belt, mechanism for advancing the belt to present the different symbols to the opening, a clock, means whereby the clock may cause the actuation of such mechanism at measured intervals, and a record sheet for workmen's entry of symbols.

95

10. In a system of the character described, the combination of a series of cryptic symbols, means for displaying said sym-

100

105

110

115

120

125

130

bols successively at measured intervals, a record sheet for workmen's entry, a casing therefor and a writing opening wherein he 5 may copy the symbol displayed and make an entry identifying himself, and means for advancing the record strip to conceal the last entry.

11. In a system of the character described, the combination of a series of cryptic symbols, means for displaying one of said symbols at a time and for displaying subsequent symbols at measured intervals, a record sheet for workmen's entries, a casing therefor and a writing opening wherein 10 he may copy the symbol displayed, make an entry identifying himself, and means at the casing connected with the record strip whereby the workman may advance the strip to move the last entry away from the 15 writing opening to conceal the same.

12. In a system of the character described, the combination of a series of cryptic symbols, means for successively displaying said symbols at measured intervals, a record sheet for workmen's entry, a casing therefor and a writing opening wherein he 20 may copy the symbol displayed and make an entry identifying himself, said writing opening having an offset portion in which 25 the workman must make an entry to complete his registration necessitating concealing such symbol before his entry is completed.

13. In a workmen's time recording system, the combination of means for displaying successively a series of code symbols at measured intervals corresponding to predetermined periods of time, and a code device for determining the symbol displayed 30 at an earlier or later time, comprising a movable member on which the symbols are displayed in their regular order and an adjacent member carrying correspondingly spaced notations of time representing said 35 intervals.

14. In a workmen's time recording system, the combination of means carrying a series of code symbols, means for display-

ing said symbols successively and at predetermined intervals including a time measuring instrument controlling the advancement of the symbols, the number of said symbols being more or less than that into which certain hour periods are divided, whereby frequent repetition of a symbol to indicate a 55 certain time is avoided.

15. In a workmen's time recording system, the combination of means carrying a series of code symbols, means for displaying said symbols successively and at predetermined intervals including a time measuring instrument controlling the advancement of the symbols, the number of said symbols being a different number than that into which certain hour periods are divided, 60 whereby frequent repetition of a symbol to indicate a certain time is avoided, and means for determining the symbol displayed at an earlier or later time, comprising relatively movable members one of which carries 65 spaces in which the symbols are arranged in their proper order and the other of which has correspondingly spaced notations arranged to correspond to the divisions of time at which the successive symbols are 70 displayed.

16. The combination with a time measuring instrument, of means carrying a series of cryptic symbols and adapted to display one at a time, mechanism for advancing said 75 means to display successive symbols at predetermined intervals, the number of symbols being out of commensurate relation to the number of intervals so that a symbol may not be repeated to represent a 80 certain time except after a large number of complete movements of the symbol carrying means, and a key to the code system thus provided, arranged to determine symbols displayed earlier or later than a given time. 85

In testimony whereof, I hereunto affix my signature.

JOHN A. DEMUTH.
